UNITED STATES PATENT OFFICE.

CHARLES FREDERICK BETTS, OF NORTH FINCHLEY, LONDON, ENGLAND, ASSIGNOR TO
DENTAL MANUFACTURING CO., LTD., OF LONDON, ENGLAND.

DENTAL CHAIR.

1,203,572.

Specification of Letters Patent.

Patented Nov. 7, 1916.

Application filed March 16, 1915. Serial No. 14,807.

To all whom it may concern:

Be it known that I, CHARLES FREDERICK BETTS, a subject of the King of Great Britain, residing at 50 Horsham avenue, North 5 Finchley, in the county of London, England, have invented new and useful Improvements in and Relating to Dental Chairs, of which the following is a specification.

My invention relates to improvements in 10 easily portable dental chairs adapted for transport purposes and capable of being easily moved from one place to another.

My invention comprises a chair seat frame hinged to a base, so arranged that when in 15 the position for use, the chair is rigid and its parts such as the chair seat, foot rest, head rest and arm rests are adjustable as in an ordinary dental chair, while when out of use the chair and seat with its head rest and 20 foot rest can be folded together without being disconnected so as to lie flat against the chair base in a very small compass.

My invention is illustrated in the accompanying drawings, in which:

25 Figure 1 shows a photographic perspective view of the chair in position for use. Fig. 2 shows a partial side view. Fig. 3 shows a sectional elevation on the line A—B of Fig. 2. Fig. 4 shows a detail view of the 30 head rest. Fig. 5 shows a detail view of the foot rest clamp. Fig. 6 shows a side elevation of the chair folded in a case adapted to form the base of the chair when in use. Figs. 7 and 8 show front and side elevations 35 respectively of the removable or auxiliary arm rest, and Figs. 9 and 10 show plan and sectional detail views of the sockets for the auxiliary arm rest.

According to my invention I rigidly 40 mount on the chair base 1 which is conveniently in the form of a case as shown in Figs. 1 and 6, pairs of supports 2 for the front legs 3 and back legs 4 of the chair. The said front and back pairs of legs are 45 respectively hinged at their lower ends to the said pairs of supports 2 and at their upper ends to pivots 5 mounted on the frame 6 of the chair seat. The length of the front pair of legs is so proportioned in relation to 50 the length of the back pair of legs 4 of the seat that when desired said seat can be folded over with its frame and reversed so as to lie flat with its legs against the chair base 1 as shown in Fig. 6. The front pair

of legs 3 of the seat are adapted to carry a 55 foot rest 7.

The inner end of the foot rest 7 is pivotally mounted upon a spindle 8 (Fig. 5) the ends of which spindle are journaled in a pair of split sleeves 9 respectively embracing the said front pair of legs 3. The frame of the said foot rest 7 is provided with a pair of suitably shaped projections or arms 10 respectively adapted to engage against shoulders 11 projecting from the 60 said split sleeves 9 embracing the front legs of the chair. When pressure is brought to bear upon the foot rest, the said projections 10 are pressed down against the shoulders 11 of said sleeves, thus causing them to grip 65 the legs of the chair and to lock the foot rest 7 in the position in which it is set. If desired, additional locking means may be employed. The upper ends of the said front pair of legs 3 are provided with latches suitably in the form of hooked members 12 as shown which if desired may be controlled by springs. The said hooked members 12 are 70 respectively adapted to engage over pins 13 projecting from each side frame 6 of the 75 seat. The said pins are preferably provided with thumb nuts 14 adapted to be screwed against said hooked members when in engagement with said pins, thus locking said hooked members and consequently locking 80 the chair seat and preventing it from collapsing into the folding position when the 85 chair is in use as shown in Fig. 1.

As shown in detail in Figs. 2 and 3, the 90 chair seat 15 is adapted to be raised and tilted to a desired position above its frame 6. The under side of the chair seat 15 is provided with a pair of lugs 16 having attached thereto heads 17 of telescoping members 18 95 adapted to telescope in the upper ends of the back legs 4 of the chair. The said telescoping members 18 are conveniently locked in position by set screw 19 when the chair seat 15 has been raised and tilted to the desired 100 position. In order to allow of said chair seat 15 being tilted the pawl 20 pivoted to the chair frame 6 is engaged with one or other of the series of ratchet teeth 21 arranged on the under surface of said seat 15.

The pawl 22 pivoted to the rear arms 23 105 of the movable arm rest 24 holds said arm rest in the position in which it is set. In order to allow of said arm rest being folded

it is mounted on parallel arms 23 with pivoted joints 44 on the upper ends of said arms and pivoted joints 45 on their lower ends. The said joints 45 are mounted upon secondary hinged pieces 46 pivoted in a plane at right angles to the said pivots 45 by means of pins 47 passing through lugs 48 on the main frame-work 6. The back end of the seat frame 6 is provided with uprights 10 25 mounted on pivots 49. The said uprights carry the sliding back 26 supported on said uprights by guides 28 and adapted to be locked in the desired position by means of set screws 27. The uprights 25 carrying the chair back are provided with pivotal ratchets 29 adapted to be engaged by pawls 30 arranged at the back of the chair seat. This pawl and ratchet mechanism allows of the angle of the back being set to 20 suit the patient.

The back is adapted to carry in a central position the sliding upright 32 on which is mounted the head rest 37 shown in Fig. 4 which is mounted upon a tubular pivot 40 25 between clamping pieces 41 and 42 and is adapted to be clamped in the desired position by means of the hand screw 43. The sliding upright 32 can be locked in the desired position by any convenient means such 30 as a set screw 38. The chair of my invention may also be fitted with removable or auxiliary arm rests 33, the ends 34 of said arm rests being adapted to rest in the sockets 35 in the chair seat, as shown in Figs. 7, 8, 35 9 and 10. The said arm rests 33 can be reversed according to the width of seat required.

What I claim is:—

1. A folding dental chair comprising a 40 base, a seat frame, a movable chair seat within said frame, means for raising said chair seat and tilting it to a desired position above said frame, a back pair of legs pivoted to said base, a front pair of legs 45 pivoted to said base and adapted to carry with said back pair of legs said seat frame and so proportioned in relation to the back pair of legs that said seat can be moved within its frame and then folded over with 50 the frame and reversed so as to lie flat with said pairs of legs against said chair base.

2. A dental chair comprising a base, a seat frame, a back pair of legs pivoted to said base, a front pair of legs pivoted to said 55 base and adapted to carry with said back pair of legs said seat frame and so proportioned in relation to the back pair of legs that said seat frame can be folded over and reversed so as to lie flat with said pairs of 60 legs against said chair base, a movable chair seat adapted to lie within said frame when reversed and to be raised and tilted to a desired position above said frame when in the extended position, a pair of lugs pivoted to 65 the underside of the chair seat, telescoping

members attached to said lugs and adapted to telescope in the upper ends of said back pair of legs, a series of ratchet teeth on the underside of said chair seat, and pawls pivoted to said seat frame and adapted to engage with one or other of said ratchet teeth.

3. A folding dental chair comprising a base, a seat frame, a movable chair seat within said frame, means for raising said chair seat and tilting it to a desired position above said frame, a back pair of legs pivoted to said base, a front pair of legs pivoted to said base and adapted to carry with said back pair of legs said seat frame and so proportioned in relation to the back pair of legs that said seat can be moved within its frame and then folded over with the frame and reversed so as to lie flat with said pairs of legs against said chair base, a pair of latches respectively pivotally mounted upon said front pair of legs, members projecting from the sides of the seat frame and adapted to be engaged by said latches and to hold said chair in the extended position.

4. A folding dental chair comprising a base, a seat frame, a movable chair seat within said frame, means for raising said chair seat and tilting it to a desired position above said frame, a back pair of legs pivoted to said base, a front pair of legs pivoted to said base and adapted to carry with said back pair of legs said seat frame and so proportioned in relation to the back pair of legs that said seat can be moved within its frame and then folded over with the frame and reversed so as to lie flat with said pairs of legs against said chair base, a pair of hooked members respectively pivotally mounted on said front pair of legs, pins projecting from the sides of the seat frame adapted to be engaged by said hooked members, thumb nuts adapted to be screwed against said hooked members when in engagement with said pins to lock said chair seat when in the extended position.

5. A folding dental chair comprising a base, a seat frame, a movable chair seat within said frame, means for raising said chair seat and tilting it to a desired position above said frame, a back pair of legs pivoted to said base, a front pair of legs pivoted to said base and adapted to carry with said back pair of legs said seat frame and so proportioned in relation to the back pair of legs that said seat can be moved within its frame and then folded over with the frame and reversed so as to lie flat with said pairs of legs against said chair base, a folding arm rest pivotally attached to the chair frame, a pawl pivoted to said arm rest and adapted to hold said arm rest in position when set for use.

6. A folding dental chair comprising a base, a seat frame, a movable chair seat

within said frame, means for raising said chair seat and tilting it to a desired position above said frame, a back pair of legs pivoted to said base, a front pair of legs pivoted to said base and adapted to carry with said back pair of legs said seat frame and so proportioned in relation to the back pair of legs that said seat can be moved within its frame and then folded over with the frame and rendered so as to lie flat with said pairs of legs against said chair base, a pair of lugs mounted on the chair seat frame, carrying

members pivoted to said lugs, parallel arms pivotally mounted on said carrying members in a plane at right angles to the pivots of 15 said carrying members and a folding arm rest pivotally mounted on said parallel arms.

In testimony whereof I have signed my name to this specification in the presence of two subscribing witnesses.

CHARLES FREDERICK BETTS.
